LIGHTING FIXTURE

Arthur E. Wiedenhoef and Harry A. Best,
Chicago, Ill.

Application June 3, 1932, Serial No. 615,125

2 Claims. (Cl. 240—78)

This invention relates in general to a lighting fixture and has more particular reference to a fixture combining the illuminating effects produced by the ordinary filament types of lamps and electrified gas filled tubing.

One of the principal objects of the invention is in the provision of a lighting fixture in which electrified gas filled tubing and electric filament lamps are combined with decorative, reflecting and refracting media to produce new and striking illuminating effects for decorative and display purposes.

A further object of the invention is in the provision of an electric fixture in which replaceable units of gas filled tubing are used.

A further object of the invention is to produce new and striking illuminative effects by the combining of electrified gas filled tubing and ordinary electric lamps with reflecting and refracting media which are transparent, translucent and opaque and in which the elements may be plain or colored to produce different illuminating effects.

A still further object of the invention is in the provision of an electric fixture combining electrified gas filled tubing with ordinary filament lamps and in disposing them relatively with respect to reflecting and refracting media and by connecting the lamps and tubing for independent illumination separately or in combination with the other lighting elements to produce different lighting effects by varying the lighting elements which are receiving current.

Other objects of the invention will appear hereinafter, the accompanying drawing illustrating more or less diagrammatically a combination of elements for producing the desired effects.

In the accompanying drawing, Fig. 1 is an elevation with parts shown in section of a fixture embodying the principles of this invention; and

Fig. 2 is a sectional plan view of the fixture.

Electrified gas filled tubing is not now commonly used for lighting fixtures for decorative and illuminative purposes principally for the reason that such tubing is neither designed nor intended to be supplied in replaceable units which may be readily applied to a lighting fixture of this type. Such tubes are used for signs, letters, and advertising and display purposes. One of the objections to the use of this tubing in electric fixtures has been that it is operated by an electric current of high voltage, requiring a transformer, which is objectionable unless the fixture is made complete in itself so that there is little or no danger in its use.

It has heretofore been considered impractical to combine gas filled tubing with the filament type of lamps in an electric fixture because the tubing when lighted usually produces a highly colored and attractive illumination which is not usually of pleasing quality for lighting purposes. However, by combining gas filled tubing units which produce illumination of various colors with reflectors of metal and glass and transparent and semi-transparent globes or shades and electric lamps of the filament type which may be either plain or colored, fixtures of various designs may be constructed in which the lighting effects produced by the combinations are extremely attractive and striking in appearance, and have sufficient illumination to produce a fixture which may be used in any desired location. In such a fixture the illumination may be varied by connecting certain of the lighting elements to different switches which may be operated at will. In other words, there may be gas filled tubes which produce different colors and filament lamps of different colors all in the same fixture combining to produce an illuminating effect which may be greatly varied to suit various conditions.

Referring now more particularly to the drawing, a fixture of the pendant or chandelier type is represented as suspended from a ceiling or other support and comprising a central structure for supporting one or more opaque reflectors 4 and 5, preferably formed of thin sheet metal, either colored, plain or coated with a highly reflecting finish such as silver or chromium.

Also supported by the central structure may be one or more transparent or translucent shades 6 of glass or the like, either plain, frosted or colored and although represented as being located below the other reflectors, lamps of different designs will have these reflecting and refracting mediums differently located, of different shapes and sizes and in different colors to produce fixtures of various types and designs.

The so-called central structure is preferably composed of tubular or hollow metal parts 7, 8 and 9 suitably connected together and providing means for carrying the reflectors and for covering and protecting the electric wiring.

A number of electric lamps 10 of the filament type are supported by the central fixture support in any suitable manner as by means of short metal fixture stems 11 secured to and projecting from the tubular parts 8 and 9. These lamps 10 may be located within the bowl 5 or the reflector 6 where they are not ordinarily seen from below or

they may project openly from a collar 12 in any desired location.

Also carried by the collar 12 are a number of sockets 13 arranged in parallel pairs for receiving the extremities 14 of a gas filled lighting tube 15 which is located immediately below the reflector shade 6 so that the color of the tube when lighted will be imparted to the shade 6 and the direct light of the tube will also be available.

10 Another set of sockets 16 is supported from the central support, as from the tubular member 8, the sockets being arranged in parallel vertical pairs to receive the terminals 17 of a gas filled tube 18. These tubes may have any desired shape or design and as represented they have upper bends 19 and 20 representing them as dipping into or extending out of the reflectors 5 and 4. A portion of each of the tubes 18 is located on the opposite side of the glass shade 6 and the illumination imparted to the shade by this tube is entirely different in character and result from that imparted by the lower tubes 15.

15

20

In order to supply current at the proper voltage and to make the fixture as safe electrically as possible, a transformer 21 may be carried in the tubular portion 8 of the central support from which conductors 22 lead through the sockets 13 and 16 to the terminals of the lighting tubes. By this construction and arrangement the transformer is located directly in the fixture and close to the tubes so that a minimum of wiring is required.

With this construction, combination and arrangement of parts it is possible to obtain a variety of direct, indirect and semi-direct lighting by means of ordinary filament lamps and gas filled tubing lights; by properly connecting the separate elements through suitable wiring and switches, the various combinations of lighting effects may be obtained from the same fixture, using each group of lamps or lights separately, or in combination with all of the others or any group of them. In this manner a striking lighting effect may be produced for the tubing lights as now employed are highly colored and when combined with the shades, reflectors and lights, of a lighting fixture in which these parts may also be separately or differently colored, the lighting effects are modified and produce fixtures 50 of great beauty.

By making the tubing light sockets in parallel pairs it is possible to provide for interchangeable tubing lights which may be quickly connected and disconnected for replacement, repair, or simply to vary the lighting effect of a fixture. 5 Lighting fixtures of this kind are particularly adapted for use in public places such as theatres, cafes, and halls where it is desired to produce a brilliant, attractive lighting effect, and at times to change the lighting effect either as to predominant color for a short interval, or to change the entire lighting effect which may include replacing the tubes and lamps with those of a different color or design. With such a construction a great variety of changes can be made with the 15 same fixture in a very short time and at a minimum of cost.

Even when the tubes are not lighted the effect which they have is decorative because they may be colored and the lighting produced by the filament lamps is modified to the extent that they shine through or upon or in combination with the colored effect produced by the tubing.

We claim:

1. In a lighting fixture comprising a support, 25 reflectors carried thereby and spaced along the support, filament lamps carried by the support and arranged inside and outside of the reflectors for direct and indirect lighting, gas filled tubing lamps also carried by the support and disposed with portions on opposite sides of the reflectors for direct and indirect lighting, and an electric transformer for the current for the tubing lamps 30 also carried by the support close to the tubes and enclosed by at least one of the reflectors. 35

2. In a lighting fixture, a support having a plurality of reflectors carried thereby, filament lamps carried by the support and arranged inside and outside the reflectors for direct and indirect lighting, gas filled tubing lamp units 40 also removably carried by the support and interchangeably disposed inside and outside of the reflectors for direct and indirect lighting, the tubing units being illuminated by the filament lamps to produce different lighting effects when 45 the tubing units are illuminated and when they are not illuminated.
